UNITED STATES PATENT OFFICE.

EDMOND E. DEAL, OF WILKES-BARRE, PENNSYLVANIA.

SAFETY SPRING.

Application filed August 1, 1923. Serial No. 655,117.

This invention relates to spring devices, and more particularly to a safety spring especially adapted for supporting porch swings and similar structures.

5 One of the main objects of the invention is to provide a device of the character stated in which a spring under tension is employed for supporting the swing so as to obtain maximum resiliency.

10 A further object is to provide simple and efficient means whereby dropping or falling of the swing is prevented in the event of breakage of the spring.

15 Another object of the invention is to so construct the device that the spring is at all times enclosed within a protecting casing so as to eliminate possibility of a person's fingers or clothing becoming caught in the spring.

20 Further objects will appear from the detail description.

In the drawings:—

Figure 1 is a side elevation of the improved safety spring.

25 Figure 2 is a longitudinal vertical section through the spring.

Figure 3 is a view in elevation of the links per se and disposed at right angles to the links as shown in Fig. 2.

30 The device includes a suspending coil spring 1 which is provided at each end with a hook 2. Within this spring 1 position a link device 3 which includes two links 4 and 5, disposed at right angles to each other

35 and inserted through each other so as to have sliding connection. Link 4 is provided at its outer end with an eye 6, link 5 being provided at its outer end with an eye 7, these eyes being formed by bending the terminal portions of the wire from which the

40 links are formed, the wire being twisted together at 8 at the outer end of each link. The links are normally positioned inside of the coiled spring 1 with the opposite ends 2

45 thereof formed at right angles to each other and connected to the links outwardly of the twisted portions 8 thereof. In order to anchor the hooked ends 2 of the spring 1, to the links 4 and 5 adjacent the outer ends

50 thereof, the said hooked ends of the spring and the twisted portions 8 of the links 4 and 5 are embedded in substantially semi-spherical moulded collars 11 and 12. When so arranged, a pair of telescopically con-

55 nected open ended tubular members 10 are passed over the coiled spring 1 enclosing the

connected links 4 and 5, and the moulded collars 11 and 12, thereon, and positioned intermediate the free outer ends 6 and 7 of the said connected links. The outer end of each 60 of the said tubular members 10 is then spun inwardly on and over the major portion of the semi-spherical surface of the moulded collars 11 and 12 for retaining the connected links, coiled spring, and tubular members, 65 in an enclosed operative relation, with the free outer ends 6 and 7 protruding at each closure end so formed by said tubular members and the moulded collars.

In practice, the suspending loop or chain 70 for the swing is secured through one eye at one end of the device, the eye at the other end of the device being attached to the swing in any suitable or preferred manner. There will be, of course, as many of the devices as 75 is desired used, preferably one at each corner of the swing.

By constructing the device in the manner illustrated and described, the spring 1 is placed under tension thus permitting maximum vertical movement of the swing so as to obtain maximum resiliency from the spring. When the spring is extended or contracted, the sections 9 and 10 of the enclosing casing telescope and these sections 85 are of sufficient length to at all times enclose the spring thus effectually eliminating possibility of the fingers or clothing of a person sitting in the swing being caught in the spring. In the event of breakage of 90 the spring, downward movement of the swing is positively limited by the links 4 and 5, these links providing a safety means to prevent dropping or falling of the swing in the event of breakage of the spring of the 95 suspending device.

The device constructed in the manner illustrated and described, can be readily produced at very small cost and can be readily applied to porch swings of standard construction. In addition to providing resilient supporting means for the swing, the device also serves to positively prevent dropping or falling of the swing in the event of breakage of the suspending springs, as above 100 noted.

What I claim is:—

In a device of the character described, the combination of a pair of connecting links having an elongated eyelet formed at each 110 of their inner ends, said links loosely connected by passing one of said elongated eye-

lets through the other of said eyelets at right angles thereto, the outer free ends of said connecting links twisted upon themselves adjacent the ends thereof and formed 5 into a pair of oppositely disposed open hooked ends, a coiled spring passed over and enclosing said elongated eyelets, the end coils of said spring formed into laterally extending hooked ends at right angles to each 10 other and connected to the oppositely disposed inner twisted portion of said open hooked ends, the twisted end portions of said connecting links with the hooked ends of said coiled spring attached thereto, em-

bedded in substantially semi-spherical 15 moulded collars, a pair of telescopically connected open ended tubular members positioned over said coiled spring moulded collars and the respective connected links intermediate the ends thereof, and the outer 20 end of each of said tubular members spun inwardly over the major portion of the semi-spherical surface of each of said collars for retaining said connecting links, coiled spring and tubular members in closed operative re- 25 lation.

In testimony whereof I affix my signature.
EDMOND E. DEAL.
